E. LARSON

SAFETY DEVICE FOR PORTABLE FIREARMS

Filed Feb. 10, 1921

FIG: 1.

FIG: 2.

FIG: 3.

Inventor

E. Larson,

By Marks Clark

Atty.

UNITED STATES PATENT OFFICE.

EDWARD LARSON, OF LERDALA, SWEDEN.

SAFETY DEVICE FOR PORTABLE FIREARMS.

Application filed February 10, 1921. Serial No. 443,989.

To all whom it may concern:

Be it known that I, EDWARD LARSON, a subject of the King of Sweden, residing at Lerdala, Sweden, have invented certain new and useful Improvement in Safety Devices for Portable Firearms, of which the following is a specification.

The present invention relates to safety devices for portable fire-arms of the kind in which members that normally lock the trigger, that is to say prevent the discharging movement thereof, are automatically released on seizing the handle of the stock at firing.

15 To make a safety device satisfactory from every point of view, it has to be simple so as not to get out of order, and it must not be rendered unserviceable through wear and tear, but on the contrary it should always be fit for action as long as the gun is capable of use in other respects, and further it must be so devised that the hammer cannot be released by a shock to the gun, or by defects occurring in the sear spring thereof.

25 In my opinion the safety devices of this kind as heretofore known do not comply with these requirements, which on the other hands are in every respect met by the device forming the object of the present invention.

Moreover, by the invention the exceedingly important advantage is attained in guns with invisible hammers, that it may be seen at once from the position of the locking members if the hammer or the hammers are cocked, that is to say, if the shots have been fired.

Thus a gun with invisible hammers provided with a safety device according to the present invention has the advantage of a gun with visible hammers, in that it can be seen at once whether a hammer is cocked or not, simultaneously as the disadvantage inherent in guns with visible hammers consisting in the hammers being easily acted upon by boughs and the like, is avoided. Furthermore, the advantage is attained, that the marksman, on having once charged the gun, can always see which shot has been discharged and which has not. This, certainly, is not possible in guns with visible hammers, without the gun being opened.

An embodiment of the invention is illustrated in the accompanying drawing.

55 Fig. 1 shows the device in elevation, the

parts assuming the positions wherein hammer is under tension.

Fig. 2, likewise, is an elevation showing the position of the parts after the discharge. Fig. 3 is a plan view of the device.

1 designates the trigger which is pivoted to the stud 2. The hammer is denoted by 3 and the sear by 14. This sear cooperates with two locking members which are formed like levers, viz. an upper one 3, 4 and a lower one 5, 6, the said levers being pivotally mounted on the same stud 7 in the housing of the gun lock. The lever 3, 4 is in the form of a double-armed bell crank lever, outer arm 4 thereof projecting through a slot in the top of the handle of the stock when the lever is in its locking position (Fig. 1), whereas the other arm 3 of the lever engages with its arch-shaped end surface 16 over the lateral abutment 8 at the rear end of the sear 14. The lever 5, 6 is also shaped like a bell crank lever and projects with its one arm 6 through a slot in the bottom of the handle of the stock, while the inner arm 5 of the lever engages with the nose 9 over the abutment 8 at the rear of the sear 14. The lever 3, 4 is actuated by the spring 10, and the lever 5, 6 by the spring 11. These springs have a tendency to bring the said levers into locking position.

The sear is so arranged that the rear thereof assumes a lower position (Fig. 2) when the hammer is cocked, and a higher position when the hammer is uncocked.

The action of the device is as follows:

Referring to Fig. 1, which shows the position of the parts when the hammer is cocked, both levers 3, 4 and 5, 6 are actuated when seizing the handle of the stock at firing, in that their outer arms 4 and 6 respectively are pressed inwardly through the pressure of the hand thereagainst. The inner arm 3 of the upper lever is then swung forward, so that the abutment 8 of the sear 14 loses the support of the curved end surface 16 of the said arm, and the lower lever 5, 6 is swung rearward, so that the nose 9 thereof is brought out of engagement with the abutment 8.

Thus the sear is no longer locked by the levers, but the shot may be discharged by pulling the trigger in known manner.

On the hammer being uncocked at the discharge of the shot the rear end of the sear 14 is brought upwards, the abutment 8 of

then coming in contact with the rear 12 of the arm 3, and also in contact 1 with the part 16 of the fore edge of the r 5 above the nose 9. Thus the two levers retained in the position into which they e brought on the release, and in which r outer arms are pressed into the stock, hat it may be seen at once that the ham- is uncocked and the shot discharged. n recocking the hammer the sear is ight back again to its lower position, and locking members (the levers) again asse the locking position under the action heir springs, the said members in this tion indicating that the hammer is ted. The upper lever must be shaped arranged so that the two arms thereof approximately of the same weight. a double-barrel guns which, as is known, e the widest use, there is arranged for 1 hammer and sear pertaining thereto, upper as well as a lower locking sear, t is to say four levers in all. The two ermost levers are arranged side by side acent to each other, and, likewise, the lowermost levers are arranged in the inner indicated in Fig. 3.

What I claim as new and desire to secure Letters Patent of the United States is:—

1. A safety device for guns, including a me, a hammer, means for holding the nmer in the cocking position, a trigger, members for locking said trigger inde- idently of each other, said locking mem- s each having a part projecting outside the handle of the stock so that the lock- members are released on seizing the ck at firing, and means for causing said king members to be locked automatically the released position after the discharge.

2. A safety device for guns including a

me, a hammer, a sear, a member locking

d sear, means for releasing said locking mber on seizing the stock at firing, and ans for causing said locking member to locked after the discharge automatically the released position, and means for re- ning the locking member automatically the locking position on recocking the nmer.

3. A safety device for guns, including a

me, a hammer, means for holding the nmer in the cocking position, means for easing the hammer, means for locking

d releasing means, said locking means

ving a part projecting outside of the han- of the stock so that the locking means

released on seizing the stock at firing,

d means for causing said locking means

be locked automatically in the released

sition after the discharge, and means for

urning the locking means automatically

the locking position on recocking the

mmer.

4. A safety device for guns, including a

frame, a hammer, means for holding the hammer in the cocking position, means for releasing the hammer, means for locking said releasing means, said locking means having a part projecting outside of the handle of the stock so that the locking means are released on seizing the stock at firing, and means for causing said locking means to be locked automatically in the released position after the discharge, said locking means consisting of two members, locking one and the same sear independently of each other, the one member projecting outside the upper surface of the stock in the locking position, while the other locking member projects outside the lower surface of the stock.

5. A safety device for guns, including a frame, a hammer, a sear, assuming a lower position, when the hammer is cocked and a higher position when the hammer is un- cocked, a member locking said sear in the lower position, means for releasing said locking member automatically on seizing the stock at firing and means for causing the sear to lock said locking member automatic- 85 ally in the released position after the dis- charge, and means for returning the locking member automatically to the locking position on recocking the hammer.

6. A safety device for guns, including a frame, a hammer, a sear, a member locking said sear, means for releasing said locking member on seizing the stock at firing, and means for causing said locking member to be locked automatically in the released po- 100 sition after the discharge, said locking mem- ber consisting of a pivotally mounted bell crank member the one arm of which pro- jects outside the handle of the stock, while 105 the other arm of the lever cooperates with the sear.

7. A safety device for guns, including a frame, a hammer, a sear, a member locking said sear, means for releasing said locking member on seizing the stock at firing, said locking member consisting of a pivotally mounted bell crank member, the outer arm of which projects outside the upper surface 11 of the handle of the stock, while the inner arm in the locking position of the member grasps over a projection on the sear, which projection, when the sear and the locking member are released holds the latter in the released position.

8. A safety device for guns, including a frame, a hammer, a sear, a member locking said sear, means for releasing said locking member on seizing the stock at firing, said locking member consisting of a pivotally mounted bell crank lever, the outer end of which projects outside the lower surface of the handle of the stock, while the inner arm by means of a nose grasps over a projection 125 on the sear, said projection in the released 130

position of the sear and the said locking member holding this latter in the released position.

9. A safety device for guns, including a frame, a hammer, means for holding the hammer in the cocking position, means for releasing the hammer, means for locking said releasing means, said locking means having a part projecting outside of the handle of the stock so that the locking means are released on seizing the stock at firing, and means for causing said locking means to be locked automatically in the released position after the discharge, said locking means consisting of two locking members 10 pivotally mounted on the same stud.

10. A safety device for double barrel guns, including a frame, a hammer, means for holding the hammer in the cocking position, means for releasing the hammer, 15

means for locking said releasing means, said locking means having a part projecting outside of the handle of the stock so that the locking means are released on seizing the stock at firing, and means for causing said locking means to be locked automatically in the released position after the discharge, said locking means consisting of two sets of locking members, a set for each of the guns, 20 each set consisting of an upper and a lower member projecting respectively outside the upper surface and the lower surface of the stock.

In testimony whereof I affix my signature in presence of two witnesses.

EDWARD LARSON.
